(57) **CLAIM**

The ornamental design for a microscope housing, as shown and described.

DESCRIPTION

FIG. 1 is a perspective view of a microscope housing of our new design.

FIG. 2 is a front view of a microscope housing of our new design.

FIG. 3 is a rear view of a microscope housing of our new design.

FIG. 4 is a right side view of a microscope housing of our new design.

FIG. 5 is a left side view of a microscope housing of our new design.

FIG. 6 is a top view of a microscope housing of our new design.

FIG. 7 is a bottom view of a microscope housing of our new design.

FIG. 8 is a perspective view of a microscope housing of our new design showing a left-shifted stage.

FIG. 9 is a perspective view of a microscope housing of our new design showing a forward-shifted stage; and,

FIG. 10 is a perspective view of a microscope housing of our new design showing a left and forward shifted stage.

The broken lines represent portions of the microscope housing and form no part of the claimed design.
